INVENTORS:

UNITED STATES PATENT OFFICE.

EDMOND BINNECHÈRE AND HENRI COCHARD, OF PARIS, FRANCE.

PHOTOGRAPH-ALBUM.

SPECIFICATION forming part of Letters Patent No. 244,357, dated July 12, 1881.

Application filed March 15, 1881. (No model.)

To all whom it may concern:

Be it known that we, EDMOND BINNECHÈRE and HENRI COCHARD, of Paris, in the Department of Seine, in the Republic of France, have 5 invented certain new and useful Improvements in Photograph-Albums; and we do hereby declare the following to be a full, clear, and exact description of the invention, such as will enable others skilled in the art to which it applies to make and use the same, reference being had to the accompanying drawings, which form a part of this specification, and in which—

Figure 1 is a perspective view of the album closed. Fig. 2 is a similar view, showing the flap and front open. Fig. 3 is a perspective view of the leaves, showing their manner of attachment to the flexible back; and Fig. 4 is a perspective view of the album open, in position for inspection of the pictures.

Similar letters of reference indicate corresponding parts in all the figures.

Our invention has relation to albums or portfolios for photographic and other pictures; and 25 it consists in the detailed construction and arrangement of parts of an album which is adapted to stand in an upright position upon a table or other support during the inspection of its contents, as hereinafter more fully described, and particularly pointed out in the claim.

In the annexed drawings, F represents the leaves, which are united by a piece of skin or other flexible fabric, f, in the manner clearly 35 shown in Fig. 3. These leaves are contained within a case composed of a stiff back, a bottom piece, two side pieces, (designated by the letter D,) and two folding front pieces, C C, hinged to the sides D. The fronts C C are 40 connected by flexible and elastic clasps E, and

are, when the album is closed, protected by the one-piece front B, which is hinged to the bottom, and over which folds the flap A, fastened by a lock or any other suitable device, b.

A strap or handle, a, is provided for conveniently carrying the album. 45

To inspect the contents of the album it is placed on a table, the flap A is unlocked or unfastened, and the front B is laid down flat on the table, as shown in Figs. 2 and 4. The flap is turned down back of the leaves, and the sides D, with their fronts C C, are turned back, (by opening the clasps E,) the sides standing at right angles to the back, but in a reversed position, as shown in Fig. 4, in which 50 position they serve as a support for the album. 55

Auxiliary sides or corners (shown at D') are provided for connecting and bracing the back and bottom, as shown in Fig. 4. These also serve as guides for the leaves in turning them down while inspecting the contents of the 60 album or portfolio. 60

Having thus described our invention, we claim and desire to secure by Letters Patent of the United States— 65

The described album or portfolio, composed of a back and bottom connected by rigid corners D', leaves F, united by a flexible back, f, folding sides D, having hinged fronts C, with clasps E, front pieces B, and flap A, the whole 70 constructed and arranged substantially as and for the purpose shown and set forth.

In testimony that we claim the foregoing we have hereunto set our hands this 3d day of July, 1880.

EDMOND BINNECHÈRE.
HENRI COCHARD.
